[57] CLAIM

The ornamental design for a shoe sole, as shown and described.

DESCRIPTION

FIG. 1 is a bottom plan view of a shoe sole showing my new design; the undulating grooves being of uniform depth; FIG. 2 is a left side elevational view thereof; FIG. 3 is a right side elevational view thereof; FIG. 4 is a front view thereof; FIG. 5 is a top view thereof; FIG. 6 is a rear view thereof; FIG. 7 is a fragmentary cross-sectional view thereof taken along line 7—7 of FIG. 1; FIG. 8 is a fragmentary cross-sectional view thereof taken along line 7—7 of FIG. 1; and, FIG. 9 is a fragmentary cross-sectional view thereof taken along line 9—9 of FIG. 1. The dotted line showing of a shoe upper element in FIG. 2 is for illustrative purposes only and does not form a part of the claimed design.
